C. COHAN.

AUTOMATIC SYNCHRONIZING MECHANISM FOR CHIME CLOCKS.
APPLICATION FILED JULY 1, 1918.

1,292,581.

Patented Jan. 28, 1919.

Fig. 1.

UNITED STATES PATENT OFFICE.

CHARLES COHAN, OF CINCINNATI, OHIO, ASSIGNOR TO THE HERSCHEDE HALL CLOCK COMPANY, OF CINCINNATI, OHIO, A CORPORATION OF OHIO.

AUTOMATIC SYNCHRONIZING MECHANISM FOR CHIME-CLOCKS.

1,292,581.

Specification of Letters Patent. Patented Jan. 28, 1919.

Application filed July 1, 1918. Serial No. 242,741.

To all whom it may concern:

Be it known that I, CHARLES COHAN, a citizen of the United States of America, and resident of Cincinnati, in the county of 5 Hamilton and State of Ohio, have invented a new and useful Improvement in Automatic Synchronizing Mechanism for Chime-Clocks, of which the following is a specification.

10 An object of my invention is to produce an improved mechanism for synchronizing the chime striking and time keeping mechanisms of chime clocks, whereby the striking mechanism after having been thrown out of adjustment and caused to strike the wrong chime at each hour quarter, will be reset automatically to strike the correct chime at each hour quarter.

15 A further object is to produce an improved mechanism for synchronizing the chime striking and time keeping mechanisms of chime clocks having chime drums which are longitudinally shiftable to change from one set of chimes to another.

20 25 In my improved mechanism the construction is such that proper chime striking adjustment is made automatically at the end of each hour.

30 In my improved construction I have provided but few new parts as additions to the usual elements to be found in quarter hour chime striking mechanisms. In the drawing Figure 1 is a fragmental front elevation of a chime clock mechanism embodying my 35 invention, and Fig. 2 is a fragmental sectional view taken on the line 2—2 of Fig. 1.

35 The form of clock movement I have chosen as an illustration of an embodiment of my invention, is provided with a drum 3 upon 40 which a series of chime hammer operating pins 4 are mounted, with a gear train and lever mounting housing 5 provided for supporting the drum.

45 In the mechanism I have illustrated, the minute hand shaft 6 is disclosed with gearing 7 between it and a shaft 8 which carries a snail 9 having the usual steps 10, 11, 12 and 13 for the first, second, third and fourth quarters of the hour. Upon these steps a 50 pin 14 which is carried by an arm 15, bears. Arm 15 is attached to arm 16 of a rack 17 which is pivotally mounted on a pin 18 extending from the front plate of the clock works. A spring 19 is provided for engagement with a finger 20 to maintain the pin 14

in engagement with the steps of snail 9. Co-operating with the teeth of rack 17 are a pawl 21 and a gathering pallet 22, the pawl having an arm 23 pivotally mounted on a pin 24 extending from the front plate of the 60 clock works, and the pallet having a finger 25 extending therefrom and secured to the end of shaft 26 of the chime mechanism gear train.

To the rear of and mounted in snail 9 are 65 a series of pins 27, 28, 29 and 30, pin 30 being set from the center a greater distance than the remaining three pins for a purpose to be hereinafter explained. In position to be engaged by these pins I have provided a strut 31 which is pivotally mounted at a point 32 upon a lever 33 which is pivotally mounted at a point 34 on the front plate of the clock works. Strut 31 is provided with a finger 35 which is held in engagement with a pin 70 36 mounted in lever 33, by a spring 37. The free end of lever 33 is provided with a forwardly extending pin 38 which bears upon the under edge of arm 23 of pawl 21 when the lever is lifted. Extending from the rear 75 of lever 33 and through a slot 39 in the front plate of the clock works is a stop plate 40 which lies in the path of a pin 41 carried by one of the gears of the gear train which actuates the chiming mechanism, during certain positions of lever 33.

80 Pivotaly mounted upon a bracket 42 adjacent to the upper edge of the front plate of the clock works, and in position to have its lower end register with slot 39, is a lever 90 43 having a spring 44 upon its pivot pin to retain the lever frictionally in any position it may be caused to occupy. The upper end of lever 43 is broadened for engagement with a pin 45 in the chime drum 3 of 95 the clock, and the lower end is provided with an outturned end 46 which is adapted to support pawl 21 from engagement with rack 17 during certain portions of the operation of the chime clock, by having a finger 47 100 which is formed with the pawl, rest thereon as shown in the drawing. The end 46 of lever 43 is joined to the lower end of said lever by an inclined portion which engages the inclined upper edge of an upwardly extending projection 49 of lever 33.

105 The action of my improved synchronizing mechanism is as follows:—The parts are shown in the positions they occupy just before the striking of the hour or fourth quar- 110

ter chime. The operation will be described as starting from this point.

As soon as pin 30 which is lifting up strut 31 and consequently lever 33, passes beyond the strut to permit it and lever 33 to drop, plate 40 is released from pin 41 of the chime gear train. Operation of the gear train now causes gathering pallet 22 to engage the teeth of rack 17, while simultaneously causing rotation of drum 3. Continued operation of the mechanism therefore causes pallet 22 to attempt to pick up the rack, but owing to the lifted position of pawl 21 this cannot be accomplished until pin 45 has passed beneath the upper end of lever 43 to cause withdrawal of end 46 from finger 47, thereby permitting the pallet to gather the teeth of the rack because of the engagement of the pawl therewith. This continues until finger 25 is caused to stop the operation of the chime gear train by its coming into contact with a pin 50 extending from the rack and which has been brought into position to be engaged thereby by the gathering of the rack teeth.

As the next or first quarter hour approaches, pin 27 gradually lifts strut 31 until pawl 21 is lifted clear of the teeth of rack 17. The released rack then drops under the pressure of spring 19 until the pin 14 of its arm 15 engages step 13 of the snail. But one tooth of the rack has by this action passed beyond the point of pawl 21. Therefore, when plate 40, which has been brought to intercept the path of pin 41 when lever 33 was raised, is dropped by the dropping of lever 33 upon the passage of pin 27 beyond the end of strut 31, pallet 22 has but one tooth to gather, thus permitting but one quarter hour to be struck.

At the second quarter or half hour, pin 28 causes the lifting of strut 31, but since pin 14 of rack arm 15 falls onto step 12 of snail 9, two teeth of the rack pass beyond pawl 21, which causes the chime to strike two quarters.

At the third quarter, pin 29 causes strut 31 and lever 33 to lift, thus permitting the rack to drop to bring pin 14 onto step 11. Three teeth of the rack are thus permitted to pass the pawl 21 so that the chime will strike three quarters.

Each time the lever 33 is lifted preparatory to the striking of the first, second and third quarter hour chime the pawl 21 is lifted far enough to release the rack, but not far enough to lift its finger 47 above end 46 of lever 43. However, as soon as pin 30 again lifts strut 31 and lever 33 preparatory to the hour chime strike, pin 38 lifts finger 47 of pawl 21 above end 46 of lever 43, projection 49 of lever 33 simultaneously pushing end 46 beneath finger 47 to support it as shown in the drawings. This action causes pin 14 of rack arm 15 to engage step

10, thus permitting four teeth of the rack to pass beneath the pawl 21 so that an hour chime of four quarters may be struck. The action of pushing the lower end 46 of lever 43 beneath finger 47, causes the upper end 70 to move toward the chime pin drum in position to be engaged by pin 45. As previously described, the pin 45 passing beneath the upper end of lever 43, causes withdrawal of end 46 and releasing of the chiming mechanism. 75

The coöperation of the parts is such that when pin 45 causes the pawl 21 to drop, the gathering of the first rack tooth by pallet 22 is started at the time the proper one of 80 the four quarters to be struck, is nearly completed, so that at the time all the teeth have been gathered up, the complete chime will have been struck. Should the mechanism have been released for striking the hour, at 85 a time when the chiming mechanism is out of adjustment, the mechanism will keep on running until the time the first quarter of the hour chime is reached, at which time pawl 21 is dropped by reason of the engagement of pin 45 on the chime drum with the upper end of lever 43. Thus by means of my improved mechanism the chime striking and time keeping mechanisms of a chime clock are automatically synchronized 95 at the end of each hour, thereby causing the mechanisms automatically to correct themselves for synchronization at any time within 45 minutes after a disturbing circumstance has destroyed the synchronization between the chime striking and time keeping mechanisms. 100

A feature of my invention is that by making the upper end of lever 43 broad as shown in Fig. 1, the drum may be shifted longitudinally to bring other chime pins into operation without throwing the synchronizing mechanism out of operation, thereby adapting my improved mechanism to use in chime clocks which are capable of producing a 110 series of different chimes by the mere shifting of the chime drum.

Having thus described my invention, what I claim is;

1. An automatic synchronizing mechanism 115 for the time keeping and chime striking mechanisms of chime clocks, consisting of a chime drum having a lever-engaging pin extending therefrom, a lever pivotally mounted on the clock works adjacent to and adapted to be engaged by the pin, a rack-engaging pawl, adapted to be held from engagement with the rack by the lever, and means adapted to place the pawl in supporting engagement with the lever at predetermined times, whereby when the drum is rotated the pin will engage the lever and release the pawl at the correct chime strike. 125

2. In combination in a chime clock, a time keeping mechanism, a chiming mechanism, 130

and a synchronizing mechanism, said chiming mechanism having a toothed rack adapted to regulate the proper chime to be struck at predetermined intervals, a pawl adapted to 5 engage the rack, and a rotatively mounted chime drum, said synchronizing mechanism consisting of a lever pivotally mounted adjacent to the chime drum and the pawl and adapted detachably to support the pawl 10 from the rack, and a pin mounted in the chime drum and adapted to engage the lever during predetermined periods of rotation of the chime drum, whereby the lever will be

operated to release the pawl, said time keeping mechanism having a lever adapted to be 15 operated at predetermined intervals to lift the pawl from the rack teeth and onto the pawl-supporting lever and at other predetermined intervals to lift the pawl to release rack teeth only.

In testimony whereof, I have hereunto subscribed my name this 28th day of June, 1918.

CHARLES COHAN.
